UNITED STATES PATENT OFFICE.

LEWIS SANDERS, OF SOUTH NYACK, NEW YORK, ASSIGNOR TO GENERAL ELECTRIC COMPANY, A CORPORATION OF NEW YORK.

MEANS FOR SUPPLYING STEAM FOR INDUSTRIAL PURPOSES FROM PRIME MOVERS.

1,081,403.

Specification of Letters Patent. Patented Dec. 16, 1913.

Application filed April 12, 1909. Serial No. 439,517.

To all whom it may concern:

Be it known that I, LEWIS SANDERS, a citizen of the United States, residing at South Nyack, county of Rockland, State of New York, have invented certain new and useful Improvements in Means for Supplying Steam for Industrial Purposes from Prime Movers, of which the following is a specification.

10 In connection with many steam power plants, it is necessary to supply relatively low pressure steam to different parts of the establishment for various purposes, for example, in textile mills to supply steam to dye kettles, in other instances to supply such steam for heating purposes. In such a plant the demand for low-pressure steam may vary between wide limits depending upon the uses to which it is put. Further, the demand for such steam is entirely independent of that on the prime mover for power. Under some circumstances the demand for one may be at a maximum while the other is at a minimum. From this it follows that the 25 ordinary mechanism which merely governs the admission of steam to the prime mover is inadequate to govern both for changes in load on the prime mover and for changes in the demand by the auxiliary devices for low- 30 pressure steam.

The object of my invention is to provide for a system or plant of the character described an improved governing mechanism which takes into account the demand on the 35 prime mover for power and that of the auxiliary devices for low-pressure steam, whereby the prime mover will effectively handle its load whatever be the amount up to its full load capacity, and the auxiliary devices 40 will receive the desired amount of low-pressure steam up to the full load capacity of the system, and this while maintaining the economy of the prime mover practically unimpaired.

45 In carrying out my invention a turbine of suitable construction is provided, such for example as a Curtis multi-stage turbine, or a Parsons reaction turbine. At some intermediate part or region in the working passage of the turbine where the normal pressure at full load, for example, corresponds approximately with that desired, a tap is made to receive one or more conduits for supplying steam for industrial purposes, or,

in other words, for supplying steam to auxiliary devices. Provision is made in the turbine and at or about the place where steam is withdrawn for maintaining a constant or approximately constant pressure region, and this irrespective of the load on the 55 turbine itself. This I accomplish by providing one or more valves in the working passage of the turbine which under the control of a regulating mechanism decrease the effective outlet for steam beyond said 60 desired constant pressure region when the pressure therein tends to fall, and which automatically increase the effective outlet for steam beyond said region when the pressure therein tends to rise. In order to distinguish this valve or valves from the other valve or valves of the turbine, it or they will be referred to as "stage valves", since they 65 operate in an intermediate part or stage of the turbine. They differ in function and 70 operation however from the ordinary stage valves now in use, because they are responsive to the quantity of steam withdrawn for the auxiliaries, whereas the ordinary stage valve is either under the control of the speed 75 governor or is responsive to a difference in pressure between two stages. In both of these latter cases they respond to the demand on the turbine for power.

The idea of drawing off a large quantity 80 of steam from a given stage or region that may be small or may be equal to the total amount entering said stage or region is an abnormal condition viewed from the standpoint of ordinary turbine practice and one 85 which the ordinary governing mechanism is totally inadequate to compensate or provide for.

Inasmuch as the pressure in the conduit carrying steam away from said region will 90 vary with the pressure in said region and with the demand for steam by the auxiliaries, I utilize this fact and control the action of said stage valve or valves by means of a regulating mechanism which is sensitive to such variations. This regulating mechanism can be made in a variety of ways. In order to make it extremely sensitive to 95 pressure changes, I divide said mechanism into parts, i.e., a primary regulator sensitive to pressure variations which has only a relatively small movement and small amount of work to perform, and a secondary regulator

controlled by the primary regulator and capable of exerting the desired amount of power and which controls the operation of the motor or motors for moving the turbine valve or valves.

The motor or motors for operating the valve or valves is or are preferably operated by fluid under pressure, such for example as steam, air, oil or water. It is preferable, but not necessary, to employ some kind of liquid under pressure, since the action of the motors can be more easily and certainly regulated than where elastic fluid is employed. However the motors are operated, the load on the regulating mechanism should be made as small as possible to insure satisfactory operation.

It is evident that where a large amount of steam is being supplied to the auxiliaries from some intermediate stage or stages, the admission valve or valves must admit a greater amount of steam for a given load on the turbine than would be the case if no steam were being withdrawn for the auxiliaries.

In addition to the stage valves, *i. e.*, those controlling the passage of fluid from the region of substantially constant pressure to a region of lower pressure, a valve is located in the conduit taking steam from said region which is also under the control of the regulating mechanism and so arranged that it participates in the control of steam passing through said conduit.

In the accompanying drawings, which are illustrative of my invention, Figure 1 is a partial sectional view of a Curtis turbine fitted with my improved governing mechanism, the latter being shown more or less diagrammatically to enable the parts to be readily understood; Fig. 2 is a horizontal sectional view of the turbine showing a number of stage valves and the motors for operating them; and Figs. 3 and 4 are modifications showing my invention in connection with a Parsons type of turbine.

1 indicates a Curtis multi-stage turbine adapted for condensing operation and having the usual casing divided by diaphragms 2 into four compartments or stages, each of which is provided with a bucket wheel 3. The exhaust passes off by the conduit 2^a. Mounted on the lower diaphragm of the stage to be controlled as to its pressure are stage valves 4 that control the passage of steam through the stage nozzles 5. The various nozzles and buckets both stationary and rotary form what is generally termed the "working passage" of the turbine. Each of the valves 4 is actuated by a fluid-pressure motor 6. Tapped into the stage in question, in this case the second, is a conduit 7 that supplies steam to the auxiliary devices requiring it. In this conduit is a slide or gate valve 8 that never quite closes

but always permits a small amount of steam to enter the conduit beyond it and maintain a pressure therein. The conduit is provided with a check-valve 9 that opens toward the auxiliaries, and also with an automatically acting valve 10 which opens when a vacuum exists in the conduit and admits air.

The primary portion of the regulating mechanism comprises a cylinder 11 containing a balanced piston valve 12 having two heads, an upper and a lower. The opposite ends of the valve are exposed to high-pressure fluid from the inlet pipe 13 by the passage 14 formed, for convenience, in the cylinder. The actuating fluid may be supplied to the pipe 13 by a pump or other means. The cylinder space between the heads is connected to the exhaust by the pipe 15. In this pipe is a spring-seated valve 16, and the tension on its spring determines what the exhaust pressure shall be. By reason of this arrangement it will be evident that the effective liquid pressure working in the system is that due to the difference between the inlet and exhaust pressures as determined by the valve 16. As an additional regulating means, a hand-actuated throttle-valve 17 is located in the exhaust pipe.

The piston-valve is provided with a stem 18 whose lower end is attached to a diaphragm 19, the under side of the latter being exposed to the pressure in the conduit 7 through the pipe 20, and the upper side to atmospheric pressure. On the stem are one, two or more weights 21 for loading the diaphragm and adjustable springs 22, one above and the other below the weights. The function of these springs is to determine the limits between which the steam pressure in the conduit 7 may vary. Without these springs (which serve to restore the diaphragm and its attached piston valve to normal positions) or some equivalent arrangement, there would be a continual hunting or surging back and forth of the parts instead of returning to positions of equilibrium as in the present case.

The heads of the piston valve 12 control ports 23 and 24, and have little or no overlap so as to render the apparatus extremely sensitive. Port 23 is connected to the right-hand end of the controlling cylinder of the secondary part of the regulating mechanism by the pipe 26, and port 24 to the left-hand end by the pipe 27. The secondary portion of the regulating mechanism comprises a cylinder 28 and a reciprocating piston valve 29 having right- and left-hand heads. The cylinder space between the heads is connected to the exhaust pipe 30 that returns the escaping fluid to the suction side of the pump for further use. The piston valve as it moves to and fro controls the passage 13.

of high-pressure fluid from the pipe 26 or the pipe 27 to the several motors which actuate the different valves. For convenience all of the ports leading to the pipes are shown as being in the same plane, but they can be distributed around the cylinder in which case the latter and also the piston valve can be made shorter. Each motor is provided with two pipes that alternately 10 convey high-pressure fluid and exhaust depending upon the direction of movement of the motor piston. The pipes 31 and 31^a convey fluid to and from the motor 32 which actuates the valve 8 in the conduit 7. The 15 next pair of pipes 33 and 33^a perform the same office for the stage-valve-operating motor 6. The succeeding pipes are similarly arranged and connected, although in the interest of clearness the motors have not been 20 shown connected thereto. The last two pipes in the series, 34 and 34^a, are connected to the motor 35 which actuates a balanced valve 38 that controls the passage of live steam from a suitable source through the 25 main 39 to the conduit 7 when the supply of low-pressure steam from the turbine is insufficient.

The corresponding faces of the piston valve 29 of the secondary regulator are separated by the same distance that separates the ports of the pipes communicating with a given motor; for example, the ports connected to pipes 31 and 31^a are separated by the same distance as corresponding faces of 35 the valve. The reason for this is that one pipe must receive high-pressure fluid while the other is open to the exhaust.

Referring to Fig. 1, 40 indicates a nozzle valve that is located in a suitable steam chest 40 41. As many of these valves may be employed as desired. The valve stem is attached to a lever 42 which co-operates with the cam 44 to open the valve, a compression spring 43 being utilized to assist in closing 45 it. The levers for the valves are operated by a shaft having the cams 44 thereon, and the shaft is moved by a hydraulic motor 45 controlled by a pilot valve and its actuating speed governor 46, the latter being driven 50 by the turbine either directly or indirectly.

The action of the apparatus is as follows: Assuming the turbine to be operating under heavy load with its stage valves open and all of the auxiliaries out of service; just as 55 soon as one or more auxiliaries are put into service by opening their controlling valves, there will be a drop in pressure in the conduit 7 and a corresponding drop in pressure on the under side of the diaphragm 19. The 60 weight 21 will then depress the piston valve 12 of the primary regulator and high-pressure fluid will enter the secondary regulator by the pipe 26 and move the piston valve 29 to the left until the right-hand face of the right-hand head uncovers the port leading

to the pipe 31^a and the right-hand face of the other head uncovers the port leading to pipe 31. When this happens, high-pressure fluid will flow from the primary regulator into and through the secondary regulator, 70 and by pipe 31^a to the motor 32 whose piston will open the valve 8 in the conduit 7. The exhaust from the motor will flow through pipe 31 into the secondary regulator and escape by the pipe 30 because its port is uncovered. The freedom of the exhaust can be controlled by the valve 47 in the pipe 30 and the rapidity of movement of the motor piston and its valve will be governed accordingly. If the opening of the valve 8 increases the pressure sufficiently in the conduit 7 to supply the auxiliaries, the diaphragm 19 will be moved up to its normal position together with the piston valve 12 of the primary regulator. If not, fluid under 85 pressure will continue to enter the secondary regulator cylinder and force its piston valve 29 still farther to the left uncovering one pair of pipes after the other and causing one motor 6 after the other to close its stage 90 valve 4 until a state of equilibrium is re-established, the supply valve or valves in the meantime admitting more steam to the turbine. If this does not satisfy the requirements of the auxiliaries, the motor 35 will 95 open the valve 38 and admit live steam to the conduit 7. During this operation as one stage valve after the other closes and the auxiliaries take more and more steam, the speed governor is opening the admission 100 valve or valves of the turbine and admitting more and more steam. It is evident that while this action is taking place the steam passing through the turbine and into the conduit will be performing useful work as 105 its pressure drops, and the remaining steam flowing through the turbine to the condenser exhaust will also be performing useful work. Also that the quantity of steam entering the turbine will be in excess of that required to 110 drive it if all the steam passed into the condenser or other exhaust.

Assuming that the demands of the auxiliaries decrease, the pressure under the diaphragm 19 of the primary regulator will increase and cause the same to rise, and high-pressure fluid will enter the cylinder of the secondary regulator at the left-hand end and start the piston valve 29 into motion toward the right. Since it is necessary for 115 a reversal in function of the several pipes 31, 31^a, 33, 33^a, etc., to take place before the motors can open the stage valves, i. e., that those pipes should convey high pressure fluid which conveyed exhaust before and vice 120 versa, the piston valve must move a distance to the right equal to the axial length of one of its heads. This introduces a time lag in the operation of the valves which in some cases is an advantage in that it prevents too 125 130

sudden operation of the parts. This lag may be eliminated, if desired, by connecting each pipe to a pair of ports located a distance apart equal to the length of the piston head, instead of connecting them to single ports. This arrangement is used with the primary piston. Assuming the piston valve 29 to have uncovered the port leading to pipe 34, the motor 35 will close the valve 38 and the exhaust of the motor will pass by the pipe 34^a to the cylinder space between the piston heads and escape by the exhaust conduit 30 therefrom. This operation is repeated for the successive stage valves providing the pressure conditions have not been reestablished. If they have, the primary regulator assumes its normal position and remains in that position until a change takes place (when it acts as before), and the piston 29 of the secondary regulator also stops. For moderate changes the piston valve of the primary regulator will only be open for short intervals and will close between the operation of the different motors both under 25 conditions of increasing and decreasing demands for steam by the auxiliaries. This action is assisted by the springs 22 which form an anti-hunting device to prevent overtravel of the parts.

30 In order to guard against an abnormal increase in pressure in the stage supplying steam to the conduit 7 should all or a large number of the stage valves be closed, an automatic valve 60 is provided that shunts 35 or by-passes steam from the second stage to the third. In this case the steam thus by-passed will do no useful work; but the effect of opening the valve will be to quickly lower the pressure in the second stage. The 40 pressure at which this valve will open can be regulated by adjusting the tension of its closing spring 61.

The vacuum-breaking valve 10 in the conduit 7 may be of any well-known construction. It should open and admit air when 45 there is a vacuum created in the conduit and close when there is a pressure therein.

Fig. 3 shows a Parsons type of turbine fitted with my improved governing mechanism. In order to provide the necessary 50 space for the stage valves 4, I may remove one or two rows of rotating vanes or buckets and one or two rows of stationary vanes or buckets, or I may locate the valves in that 55 part of the casing where the diameters of the rotor and casing increase. The valves 4 are of sufficient length to cover a number of stationary vanes or buckets 51 so that the effective steam outlet from the stage or 60 region 52 of constant or approximately constant pressure can be changed. Each valve is actuated by a hydraulic motor 6 which may be of the type shown in Fig. 1. Fluid is conveyed to and from the motor or motors 65 by the pipes 33, 23^a, etc., arranged and con-

trolled in the manner previously stated. Steam is withdrawn for the auxiliary devices by the conduit 7.

In Fig. 4 I have shown a further modification as applied to a Parsons type of machine wherein the rotor and casing are divided into two parts or sections 53 and 54 with an intermediate pressure region 52 between which may be regarded as part of the last stage of the high-pressure section. 70 Steam enters the conduit 55 from the high-pressure section and enters the low-pressure section through passages 56 under the control of one or more stage valves 4 that are actuated by motors 6. As the general operation of these modifications is the same as described in connection with Fig. 1, further description is unnecessary.

In accordance with the provisions of the patent statutes, I have described the principle of operation of my invention, together with the apparatus which I now consider to represent the best embodiment thereof; but I desire to have it understood that the apparatus shown is only illustrative and that the 90 invention can be carried out by other means.

What I claim as new and desire to secure by Letters Patent of the United States, is—

1. In combination, a prime mover having a high pressure admission and a low pressure exhaust, a conduit separate from said exhaust and receiving steam from the prime mover at an intermediate pressure for industrial purposes, passages in the turbine leading from the region of intermediate pressure, valve means for controlling the passages and for maintaining the supply of steam to the conduit at a substantially constant pressure, and a regulating mechanism for automatically controlling the action of 105 the valve means.

2. In combination, a prime mover having a high pressure admission and a low pressure exhaust, a conduit taking steam from a region in the prime mover intermediate 110 the admission and exhaust, a working passage within the turbine, means sensitive to a condition of the steam withdrawn by the conduit, and a valve for regulating the flow of steam through the passage from said region to the low pressure portion of the turbine and for controlling the pressure in said 115 region.

3. In combination, a prime mover, a conduit receiving fluid from the prime mover 120 at a point intermediate its supply and exhaust and after it has performed work in said prime mover, means acting on the fluid passages within the turbine for controlling the passage of fluid therethrough and also 125 into the conduit, and a regulator sensitive to a condition of the fluid flowing through the conduit for determining the effective action of said means.

4. In combination, a prime mover that is 130

divided into stages and has fluid discharging devices for each stage, a conduit receiving elastic fluid from one of the stages after it has performed work in the prime mover, 5 means for regulating the passage of fluid through the device leading from the stage that supplies the conduit, and a regulator sensitive to the passage of fluid through the conduit for modifying the position of said 10 means.

5. In combination, a turbine wherein a drop in pressure takes place between the supply and the exhaust, a conduit receiving steam from the turbine at a point intermediate the supply and exhaust, valve means carried by the turbine for controlling the flow of steam through a passage therein and also through the conduit, and a regulator sensitive to a condition of the steam 20 flowing through the conduit for regulating the action of the valve means.

6. In combination, a turbine wherein a drop in pressure takes place between the supply and the exhaust, a conduit receiving steam from the turbine at a point intermediate the supply and exhaust, a valve means carried by the turbine for controlling the flow of steam through the passages leading to the low pressure portion of the turbine 30 and also through the conduit, means for actuating said valve means, and a regulating device sensitive to a condition of the steam passing through the conduit for controlling the action of said means.

35 7. In combination, a turbine wherein a drop in pressure takes place between the supply and the exhaust, a conduit receiving steam from the turbine at a point intermediate the supply and exhaust, independent 40 valves controlling the passage of steam through the turbine and also through the conduit, motors for actuating the valves, and a regulating mechanism sensitive to a condition of the steam withdrawn by the 45 conduit for controlling the action of said motors.

8. In combination, a prime mover having a working passage through which the steam flows, a governing means for controlling the 50 admission of fluid thereto in accordance with the demand for motive power and also to the demand for steam withdrawn, a conduit that conveys steam from a given region in the turbine and at a pressure intermediate that of its supply and exhaust, and a means responsive to a condition of the steam flowing through the conduit for varying the effective area of the working passage in the prime mover on the low pressure side of said region.

9. A turbine having an admission, an exhaust, and a working passage wherein there is a region of intermediate pressure, in combination with a governing mechanism responsive to changes in speed of the turbine

for controlling the admission of steam thereto, a conduit receiving steam from said region, and a governing mechanism for maintaining a substantially constant pressure in said region, the said mechanism comprising a regulator sensitive to pressure conditions, and mechanism controlled by the regulator and including a valve carried by the turbine for increasing or decreasing the effective area of the working passage of the 70 turbine on the low pressure side of the said region. 75

10. A turbine having an admission and an exhaust, a working passage wherein there is a region of intermediate pressure, and a governing mechanism responsive to load changes on the turbine, in combination with a conduit receiving steam from said region, and a governing mechanism comprising a regulator responsive to pressure changes in 80 the conduit, one or more stage valves, and means for actuating the valves. 85

11. A turbine having an admission and an exhaust, and a working passage wherein there is a region of intermediate pressure, 90 in combination with a conduit receiving steam from said region, a valve in said conduit, a fluid motor for operating it, a controlling valve therefor, and a regulator sensitive to pressure changes for actuating 95 the said controlling valve.

12. A turbine having an admission and an exhaust, and a working passage wherein there is a region of intermediate pressure, in combination with a conduit receiving 100 steam from said region, a valve in said conduit, a means for operating it, valve means controlling the effective area of the working passage beyond said region, and a regulator responsive to a condition of 105 the steam in the conduit for controlling the valve in said conduit and the valve means.

13. A turbine having an admission and an exhaust, and a working passage wherein there is a region of intermediate pressure, 110 in combination with a conduit receiving steam from said region, means for varying the effective area of the working passage on the low pressure side of said region, a main delivering steam to the conduit from a 115 source of higher pressure, a valve in said main, and regulating mechanism for said means and the valve which is sensitive to pressure changes.

14. A turbine having an admission and an 120 exhaust, and a working passage wherein there is a region of intermediate pressure, in combination with a conduit receiving steam from said region, valves for varying the effective area of the working passage on 125 the low pressure side of said region, a valve in said conduit, actuators for the valves, and a governing mechanism responsive to the pressure of the steam in the conduit that is common to the actuators. 130

15. In combination, a turbine having a working passage wherein a drop in pressure takes place between the admission and the exhaust, a conduit taking low pressure steam from a region of the working passage intermediate the admission and the exhaust, a speed responsive governor which regulates the initial admission of steam to the turbine and thereby regulates the supply received by said region, valves for regulating the pressure in said region by controlling the flow of the steam therefrom toward the exhaust, a pressure responsive mechanism connected to the conduit and said region which opens the valves when the pressure therein tends to rise and closes them when the pressure tends to fall.

16. A turbine having an admission and an exhaust, and a working passage wherein there is a region of intermediate pressure that is to be maintained substantially constant, in combination with a conduit receiving steam from said region and supplying it to auxiliaries, valves for varying the effective area of the working passage on the low pressure side of said region, a valve in the conduit, actuators for the valves, a source of power for the actuators, and a regulator sensitive to a condition of the steam for controlling the application of power from said source to the actuators.

17. A turbine having an admission and an exhaust, and a working passage wherein there is a region of intermediate pressure, in combination with a conduit receiving steam from said region, valves for varying the effective area of the working passage on the low pressure side of said region, a valve in said conduit, motors for actuating the valves, a controlling cylinder, pipes connected to the cylinder and the motors, a valve in the cylinder for admitting fluid under pressure to the pipes and exhausting it therefrom, and a regulator sensitive to the pressure of the fluid passing through the conduit for controlling the movements of the valve in said cylinder.

18. A turbine having an admission and an exhaust, and a working passage wherein there is a region of intermediate pressure, in combination with a conduit taking steam from said region, valve means for automatically maintaining a substantially constant pressure in said region, and a valve which opens under abnormal pressure in said region and discharges steam from it to a point of lower pressure.

19. A turbine having an admission and an exhaust, and a working passage wherein there is a region of intermediate pressure, in combination with a conduit taking steam from said region, valve means for maintaining a substantially constant pressure in said region, and a valve in the conduit which opens to admit air when a vacuum is created therein.

20. A turbine having an admission and an exhaust, and a working passage wherein there is a region of intermediate pressure that is to be maintained substantially constant, in combination with a conduit receiving steam from said region and supplying it to auxiliaries, valve means responsive to a condition of the steam flowing from said region into the conduit for regulating the pressure thereof, and a device for preventing the overtravel of said valve means.

21. A turbine having an admission and an exhaust, and a working passage wherein there is a region of intermediate pressure that is to be maintained substantially constant, in combination with a conduit receiving steam from said region and supplying it to auxiliaries, valve means responsive to a condition of the steam supplied from said region to the conduit for regulating the pressure therein, and a valve in the conduit which closes when the turbine creates a suction on the auxiliaries.

22. A turbine having an admission and an exhaust, and a working passage between the admission and the exhaust wherein there is a region of intermediate pressure, in combination with a governing mechanism for regulating the admission of live steam to the turbine, a conduit receiving low pressure steam from said region and delivering it to auxiliaries, and valve means carried by the turbine for varying the cross-section area of the working passage and responsive to a condition of said low pressure steam for automatically maintaining a substantially constant pressure in said region.

23. In combination, a turbine that is divided into stages, a conduit for conveying steam from the turbine from between certain of its stages, a valve within the turbine for controlling the passage of fluid from one stage to another, a motor for actuating the valve, and means sensitive to the pressure of the steam in the conduit for controlling the action of the motor.

24. The combination with a multi-stage turbine having nozzles and bucket wheels, of a pipe taking steam from a low pressure stage therein, a regulator normally exposed to the pressure in said stage, and valves controlled by the regulator for controlling the passage of steam from said stage through the nozzles leading to the adjacent stage of lower pressure.

25. In combination, a turbine having an admission, an exhaust and a working passage between the admission and the exhaust wherein there is a region of intermediate pressure, a conduit for conveying low pressure steam from said region to auxiliaries, valve means within the turbine that controls the flow from said region to the portion of the working passage beyond the region, and means responsive to a condition of the low

pressure steam for controlling the valve means to maintain a substantially constant pressure in said region.

26. In combination, a turbine having an admission, an exhaust and a working passage between the admission and the exhaust wherein there is a region of intermediate pressure, a conduit for conveying low pressure steam from said region to auxiliaries, 10 automatic valve means within the turbine for diverting more or less steam from the portion of the working passage beyond said region to the conduit, and a device responsive to a condition of the low pressure steam 15 for controlling the valve means to maintain the low pressure steam at a substantially constant pressure.
27. In a multi-stage turbine, a dividing partition between two adjacent stages, a 20 port located on the admission side of said partition for delivering fluid from said turbine, passage means conveying fluid from one side of the partition to the other, and valve means for said passage means, the 25 operation of which is dependent upon the pressure on the admission side of said partition for controlling the delivery of fluid from one side of the partition to the other.
28. In a turbine, means for dividing the

interior passages of the turbine into two 30 parts, a port located in the turbine casing on the admission side of said means for delivering fluid from said turbine to a source of consumption outside the turbine, a port in the dividing means whereby steam may pass 35 from one part of the turbine to the other, and valve means for maintaining a constant pressure in that part of the turbine from which the first named port leads, said valve means being controlled by the pressure to 40 determine the effective port area of the second mentioned port.

29. In a turbine, means for dividing the interior passages of the turbine into two parts, a port located in the turbine casing on 45 the admission side of said means for delivering fluid from said turbine, and valve means for maintaining a constant pressure in one of the parts of said turbine and for controlling the delivery of fluid from one part to 50 the other.

In witness whereof, I have hereunto set my hand this 10th day of April, 1909.

LEWIS SANDERS.
